[57] CLAIM

The ornamental design for a child's play pool, as substantially shown and described.

DESCRIPTION

FIG. 1 is a perspective view of a child's play pool showing my new design;

FIG. 2 is a front elevational view, the rear view being a mirror image thereof;

FIG. 3 is a side elevational view, the opposite side being a mirror image thereof; and

FIG. 4 is a bottom plan view thereof.

FIG. 1

FIG. 2

FIG. 2
